US00D576569S

(12) **United States Design Patent**
Chen et al.

(10) **Patent No.:** US D576,569 S
(45) **Date of Patent:** ** Sep. 9, 2008

(54) **LIGHT EMITTING DIODE**

(75) Inventors: **Chen-Lun Hsing Chen**, Taoyuan Hsien (TW); **Hsu-Keng Tseng**, Taoyuan Hsien (TW); **Jung-Hao Hung**, Taoyuan Hsien (TW); **Fong-Luan Lee**, Taoyuan Hsien (TW)

(73) Assignee: **Prolight Opto Technology Corporation**, Taoyuan Hsien (TW)

(**) Term: **14 Years**

(21) Appl. No.: **29/287,336**

(22) Filed: **Jul. 25, 2007**

(51) **LOC (8) Cl.** 13-03

(52) **U.S. Cl.** D13/180

(58) **Field of Classification Search** D13/180; D26/2; 257/79, 80, 81, 88, 89, 95, 98, 99, 257/100; 313/483, 498, 500; 362/555, 800

See application file for complete search history.

(57) **CLAIM**

The ornamental design for a light emitting diode, as shown and described.

DESCRIPTION

FIG. 1 is a perspective view of a light emitting diode (LED) showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof wherein the broken lines form no part of the claimed design.
